CLAIM

The ornamental design for a combined golf club head and holographic insert, as shown and described.

DESCRIPTION

FIG. 1 is a perspective view of a combined golf club head and holographic insert showing my new design;

FIG. 2 is a front elevational view thereof;

FIG. 3 is a front elevational view of the holographic insert shown for clarity of illustration;

FIG. 4 is a rear elevational view of FIG. 3;

FIG. 5 is a front edge view of FIG. 3, the undisclosed opposite side being identical; and,

FIG. 6 is a side edge view of FIG. 3, the undisclosed opposite side being identical.
